UNITED STATES PATENT OFFICE

116,743

DESIGN FOR A PLATE OR SIMILAR ARTICLE

Doris Johnson, New Brighton, Pa., assignor to Mayer China Company, Beaver Falls, Pa., a corporation of Pennsylvania

Application January 14, 1939, Serial No. 82,359

Term of patent 14 years

To all whom it may concern:

Be it known that I, Doris Johnson, a citizen of the United States, residing at New Brighton, Pennsylvania, have invented a new, original, and ornamental Design for a Plate or Similar Article, of which the following is a specification, reference being had to the accompanying drawing, forming part thereof.

The drawing is a top plan view of a chinaware plate showing my new design.

The dominant feature of the design is the ornamentation appearing on the article, and while shown applied to a plate said ornamentation is intended to be applied to other similar articles.

I claim:

The ornamental design for a plate or similar article, substantially as shown and described.

DORIS JOHNSON.
